WAR MEMORIAL PICTURE FRAME

John Niver Scism, Chester, Pa.

Application February 10, 1949, Serial No. 782

Term of patent 14 years

(Cl. D29—20)

To all whom it may concern:

Be it known that I, John Niver Scism, a citizen of the United States, residing at Chester, in the county of Delaware and State of Pennsylvania, have invented a new, original, and ornamental Design for War Memorial Picture Frames or the like, of which the following is a specification, reference being had to the accompanying drawing, forming part thereof.

In the drawing:

Fig. 1 is a front view of a war memorial picture frame, showing my new design;

Fig. 2 is a side view of the same; and

Fig. 3 is a rear view.

I claim:

The ornamental design for a war memorial picture frame or the like, as shown.

JOHN NIVER SCISM.
